UNITED STATES PATENT OFFICE

2,419,396

RETARDED SHADED POLE MOTOR

Nils Pontus Wilhelm Frisk, Stockholm, Sweden,
assignor to Telefonaktiebolaget L. M. Ericsson,
Stockholm, Sweden, a company of Sweden

Application February 16, 1944, Serial No. 522,685
In Sweden January 5, 1943

2 Claims. (Cl. 172—239)

1

The invention relates to an A. C. relay of the Ferrari type operating with time retardation, in which the magnetic fluxes, causing the driving torque and being out of phase in relation to each other, are produced by a winding assembly comprising a primary winding connected to A. C. tension and two secondary windings, each of which encloses a portion of the flux produced by the primary winding and penetrating the disc. This kind of relay may be employed as an intermediary relay between a contact device which is actuated by a magnitude to be controlled and for instance a contactor which is actuated by the motion of the disc thereby making the desired switching. The invention is characterized by a device (for instance a cam disc) being moved by the rotation of the disc and controlling a switching device which is arranged to control the circuits being connectable to the respective secondary windings.

The invention will now be described more particularly with reference to the accompanying drawing in which Fig. 1 is a perspective view showing the relay and the circuits connected thereto. Fig. 2(a-c) are end views showing different positions of the cam disc provided on the shaft of the rotor disc and the contacts operated by said disc. Fig. 3 shows in perspective a modification of the invention whereby the shaft of the rotor disc is adapted to operate a rheostat. Fig. 4(a-c) are end views of the switching device and a diagram showing a further modification of the invention in which the shaft of the rotor controls the switching in of an effect in two steps. The magnet core is provided with the centre limb 1 supporting the winding 2 and the side limbs 3 and 4 supporting the windings 5, 6, respectively. 7 indicates a return plate, 8 the rotor disc. The motion of the disc is transmitted over the gear 9 to the shaft 11, which is provided with a cam disc 12 disposed to co-operate with the spring group 13, 14, 15. The shaft 11 is assumed to actuate a contactor, for instance a mercury switch. The winding 2 is assumed to be connected to an A. C. tension over the terminals 16. Furthermore, the windings 5 and 6 may be short-circuited alternatively over the lines L1 and the remote lines L2 by the break-make contact 21, 22, 23 inserted in a transmitter. When the contact between the springs 21 and 22 is closed the winding 5 is short-circuited and, when a contact between 21 and 23 occurs, the winding 6 is short-circuited. Moreover, the windings 5 and 6 may be alternatively short-circuited over the lines L3 and the break-make contact 13—15 over a great resistance R.

2

The spring assembly 21—23 is assumed to be actuated by e. g. a thermostat which, at a given temperature, closes the contact 21—22 and, at another temperature, closes the contact 21—23.

5 The device may be employed for instance for adjusting radiator heaters, the contact 21—22 thereby being closed by a heat sensitive device such as a thermostat when the temperature exceeds a certain value, the disc thereby turning 10 in one direction and the shaft 11 operating the radiators so that the heat supply decreases whilst, when the temperature falls below a certain value, the contact 21—23 is closed, thus by the turning of the disc in opposite direction increasing the 15 heat supply. The device operates in the following manner. When the temperature is invariable the spring 21 in the transmitter G has its middle position and the cam disc 12 a position as shown in the centre detail of Fig. 2, in which position the 20 spring 14 does not make contact with any of the springs 13 and 15. The disc 8 then has its zero position and is influenced only by the flux from the winding 2 which flux, upon penetrating the disc, branches symmetrically to the limbs 4 and 3, 25 no driving torque thereby being produced. Should now, on exceeding the given temperature, for instance, the winding 5 be short-circuited by the contact 21—22, a dissymmetry follows in the fluxes which produces a clockwise operating driving torque causing the disc 8 to rotate. As soon as the disc leaves its zero position the cam disc 12 closes the contact 13, 14 so that the winding 6 is short-circuited over resistance R. This position of the cam disc and the springs is shown in 30 Fig. 2a. Thus, the disc will be influenced by a driving torque in the opposite direction which torque, however—the resistance R having a high value—does not suffice to overcome the first torque. Consequently, the disc 8 will turn clockwise until the shaft 11 produces a decrease of the 35 heat supply in which position the shaft 11 is arrested by means of a cam 31 on the disc 12 engaging a stop 33 as shown in Fig. 2a-c. When the temperature later becomes normal and the contact 21—22 is broken, the short-circuiting for the 40 winding 5 is broken. The driving torque produced by the dissymmetry caused by the flux from the winding 5 thus ceases and now the disc is operated only by the torque caused by the winding 6 and operating in the opposite direction which torque is sufficient to restore the disc to its zero position, in which position the cam disc 12 breaks the contact 13—14 so that the winding 6 is no more short-circuited over resistance R, 45 the movement of the disc thus being stopped.

55

The cam disc 12 and springs 13—15 now take the position shown in Fig. 2b. Should instead the temperature have fallen below the value given, the contact 21, 23 would have short-circuited the winding 6 and the disc would have rotated counter-clockwise until a switching operation corresponding to a rise in temperature had been performed by the shaft 11, the disc 8 then would have been restored to its starting position which restoring in this case would be due to the short-circuiting of the winding 5 over the contact 14, 15. This position of the cam disc and springs is shown in Fig. 2c, the movement having been stopped by means of the cam 31 engaging a stop 32. Each time a switching operation takes place the disc thus will be restored to its zero-position.

In the embodiment now described the relay as shown in Fig. 4a-c may be adapted in two steps to switch in a resistance comprising two parts 41, 42, said switching being performed by means of an arm 40 connectable to three contacts 43, 44, 45, the contact position 21—22 thereby corresponding to the starting position, the centre position of spring 21, giving no contact, corresponds to the first step and the contact position 21—23 to the second step. In the starting position, e. g. the contact position 21—22 the winding 5 is short-circuited and thus the disc has one of its outer positions no part of the resistance being switched in, as shown in Fig. 4a. When the spring 21 during the influence of the controlling magnitude is brought to its centre position the disc, on account of the winding 6 by means of the cam disc being connected to the resistance R, is brought to its centre position where it remains. During the motion, the arm 40 engages contact 44 thereby switching in one half of the resistance 42, Fig. 4b. When thereafter, during a further change in the controlling magnitude, the spring 21 makes contact with the spring 23, the winding 6 is short-circuited and the disc turns in the same direction as before to its other outer position, the arm 40 thereby engaging the contact 45 so that the entire resistance 41—42 is connected.

The arrangement according to the invention may also be modified in such a manner shown in Fig. 3 on the drawing that the resistance R is short-circuited and the contact springs 13—15 and 21—22 respectively may be dispensed with, the points 13¹, 15¹ being connected to the end points of one potentiometer resistance P₁ and 22¹ and 23¹ to the end points of another potentiometer resistance P₂, whilst the point 14¹ is connected to the sliding contact 25 of one potentiometer P₁ and 21¹ to the sliding contact B of the other potentiometer P₂. The sliding contact of the potentiometer P₁ is controlled by the shaft 11 and the sliding contact of the other potentiometer P₂ is controlled by the thermostat G. By a suitable gearing of the motion of the sliding

contact of the potentiometer P₁ in relation to the rotatable part of the relay a conformity of motion is obtained between the potentiometer P₂ and the rotatable part. If there is an unbalance between the potentiometers, the current intensity in one of the windings 5 or 6 prevails, which results in a turning of the disc 8 until the sliding contact of the potentiometer P₁ has been displaced so much that the current intensities through the windings 5 and 6 are equal and the disc stops. Should the sliding contact of the potentiometer P₂ then change position, the balance will be disturbed anew, causing the disc again to move until balance follows.

15 I claim:

1. In an alternating current relay, a main winding adapted to be energized by alternating current, secondary coils adjacent said winding, a rotor rotatable upon short circuiting one of said secondary coils, a resistance, and means operated by rotor rotating incident to short circuiting of one of said secondary coils to connect the other secondary coil with a resistance whereby the second mentioned secondary coil exerts a driving torque on said rotor in opposition to and of less value than the rotating influence of the short circuited secondary coil.
2. In an alternating current relay, a rotor, a main winding adapted to be energized by alternating current, secondary coils operable when alternately short circuited to cause the rotor to rotate in opposite directions, a resistance, and means operated by the rotor rotating in either direction incident to short circuiting of one of said secondary coils to connect the other secondary coil with a resistance whereby the second mentioned secondary coil exerts a driving torque on said rotor in opposition to and of less value than the rotating influence of the short circuited secondary coil.

NILS PONTUS WILHELM FRISK.
